UNITED STATES PATENT OFFICE.

JAMES H. CARY, OF MEMPHIS, TENNESSEE.

ROTARY BRUSH.

1,231,491.

Specification of Letters Patent. Patented June 26, 1917.

Application filed July 22, 1916. Serial No. 110,633.

To all whom it may concern:

Be it known that I, JAMES H. CARY, a citizen of the United States, residing at Memphis, in the county of Shelby and State of Tennessee, have invented certain new and useful Improvements in Rotary Brushes, of which the following is a specification.

My invention relates to certain new and useful improvements in rotary brushes, and 10 the invention consists, essentially, of a brush having its circumference provided with a series of parallel longitudinally extending brush backs or strips provided with bristles, which stand at an angle or tangential to the 15 circumference of the brush, said brush backs being separated from each other to form intermediate spaces for the free admission and circulation of air into and through the brush.

20 The invention further consists of the parts and the constructions and combinations of parts which I will hereinafter describe and claim.

In the drawing forming part of this specification the figure represents a cross-sectional view of a rotary brush embodying my invention.

In carrying out the invention above named, I form the brush of suitable heads, 30 which are made of wood or of any desired material and proportions, and which heads may be reinforced or strengthened by a flange or disk, E, being bolted to the central portion thereof, said disk having a central opening, E', for the reception of a suitable shaft, by which the brush may be rotated.

The circumference or edge of each head employed in the construction of the brush, 40 is recessed to a substantial depth to form the inclined walls, 2, 3, which are arranged one at right-angles to the other, said recesses being provided for the reception of the series of similarly-shaped longitudinally extending brush-backs, or sticks, b, from the rear edges of which suitable bristles project at an angle so as to stand at a tangent to the circumference of the brush, these bristles pointing backwardly or oppositely to the 50 direction in which the brush is to be rotated, and said bristles serving to impart a wiping effect against any surface or object with which they contact.

The brush-backs are by reason of the 55 aforesaid recesses formed in the heads spaced from each other equi-distant around the

heads, and a clear unobstructed space, d, is thus expressly provided between adjacent brush-backs, or sticks, and leading into the hollow interior of the brush so as to permit 60 the free entry and circulation of air into and transversely through the brush, a condition which is of importance in some arts, and particularly where the brush is used in connection with cotton-gin-feeders, as for instance, shown and described in my copending application filed July 6, 1916, Ser. No. 107,766, where such a brush as I have described is illustrated in association with a toothed drum or cylinder and a current of 70 air is induced through the brush for the purpose of carrying off any hull-particles which may be mixed with seed-cotton. However, my improved brush is not limited to this art, or to any particular art, it being my intention 75 to employ it wherever its construction may be found useful.

A brush such as has been described and one where the brush has its bristles or brush matter arranged at an angle of say about 80 45 degrees to the plane in which the brush rotates, is important in the cotton industry, because such a brush does not gin the cotton or damage the staple in taking it off the toothed cylinders, with which cotton 85 gins are usually supplied.

The brush heads or sticks may have an outer face provided with a metal reinforcing plate, C, which extends throughout the length of the head or stick and through this 90 plate and the stick and into the heads of the brush suitable fastenings as screws or nails, e, may pass to secure the sticks firmly in place.

Also, if desired, I may place inside the 95 brush on the shaft, on which the brush is mounted suitable floating rings, g, or the like for the purpose of keeping lint from wrapping around the shaft, if the brush is used in cotton gin feeders or similar machines, as before mentioned.

Having thus described my invention what I claim as new and desire to secure by Letters Patent is:—

1. A rotary brush comprising suitable 105 heads and brush-backs secured thereto in spaced relation, said brush-backs having two adjacent angular faces, and provided with projecting bristles, said heads having recesses in their edges with two walls only for 110 receiving the corresponding faces of the brush-backs, the spaces between adjacent

backs permitting an air current to be discharged transversely through the brush.

2. A rotary brush comprising suitable heads and brush-backs secured thereto in spaced relation, said brush-backs having two adjacent angular faces, and provided with projecting bristles, said heads having recesses in their edges with two walls only for receiving the corresponding faces of the

brush-backs, the spaces between adjacent brush backs permitting an air current to be discharged transversely through the brush, plates extending longitudinally along the outer faces of the backs, and fastening devices for securing the backs to said heads. 10 15

In testimony whereof I affix my signature.

JAMES H. CARY.
